UNITED STATES PATENT OFFICE.

WILLIAM W. BARRY, JR., OF DETROIT, MICHIGAN, ASSIGNOR TO WIL BAR MANUFACTURING COMPANY, OF DETROIT, MICHIGAN, A CORPORATION OF MICHIGAN.

PUSH-BUTTON.

1,128,744.

Specification of Letters Patent.

Patented Feb. 16, 1915.

Application filed March 7, 1914. Serial No. 822,270.

To all whom it may concern:

Be it known that I, WILLIAM W. BARRY, Jr., a citizen of the United States, residing at Detroit, county of Wayne, State of Michigan, have invented a certain new and useful Improvement in Push-Buttons, and declare the following to be a full, clear, and exact description of the same, such as will enable others skilled in the art to which it pertains to make and use the same, reference being had to the accompanying drawings, which form a part of this specification.

This invention relates to electric bell fixtures and has for its object a push button switch in which all the elements can be assembled before the switch is applied to the wall.

In the drawings,--Figure 1, is a vertical section before assembling. Fig. 2, is a vertical section after the switch has been applied to the wall. Fig. 3, is a plan view. Fig. 4, is a plan view of a modified form. Fig. 5, is a vertical section of a modified form. The casing *a* of sheet metal is pressed into the proper shape by suitable dies and comprises a bell-shaped portion which has its rim flaring out to form a flange *b*. The end of this flange is turned over to form a spacing ring *c*. The spacing ring *c* keeps the annular flange *b* properly spaced from the wall of the building, casement, or other support to which the switch is to be attached. The binding posts *e* and *f* are attached to a cross-strip *g* of insulating material. This cross-strip *g* is bowed inward at the center so that the binding posts are held out of contact from the wall, as shown in Fig. 2. The binding post *e* carries the spring contact *h*, this contact fitting over the inward end of the binding post and being held in place by the nut *j*. The free end of the binding post is in the form of a loop, the arm of which can be pushed into contact with the binding post *f* by the push button *i*. The resiliency of the spring contact *h* normally holds the push button projected outward in the casing *a* as shown in Fig. 2.

The cross-strip *g* may be attached to the casing *a* before the push button switch is applied to the wall. This is a matter of great convenience as the assembled bells may then be carried in the electrician's pocket or in any other manner without requiring first the picking out of the parts

and putting them together to apply to the wall. This assembly is effected in a very simple manner for the ends of the strip *g* are perforated and the spacing ring *c* has a pair of diametrically opposite integral ears *k*. These are perforated by having the metal cut and forced out at one side as shown in the drawings, forming prongs *l*. Perforations *m* are made in the annular flange directly opposite the perforations *l* in the ears. These perforations are made in the same manner and have similar prongs. These prongs fit into the perforations in the ends of the cross strip *g* and when the cross strip *g* has been placed against the annular flange the ears *k* may be turned over, as shown in Fig. 2 and the prongs *l* of the ears *k* slipped into the perforations of the strip. This firmly holds the strip in place so that the switch is completely assembled. When it is applied to the wall, all that is necessary is to attach the wires *n* to the binding post and screw the casing to the wall by means of the screws *o*.

In Figs. 4 and 5 a similar form of construction is shown, except that in this case the switch casing *a* has an escutcheon *p* which is shaped by suitable dies so that the escutcheon is provided near the switch casing with a boss *q*. To this is riveted or screwed the cross-strip *g*. The boss *q* enables the cross-strip to be carried in a spaced relation with respect to the wall so that the binding screws are held out of contact with the wall to prevent moisture from following the wall down and short-circuiting the bell.

What I claim is:

1. A push-button switch, having in combination, a casing, a cross strip of insulating material bowed at its center, said cross strip and casing being arranged so that the cross strip may be secured to the casing before the same is applied to the wall, binding posts carried by the bowed portion of the cross strip, a contact spring attached to one binding post, and a push button for forcing the contact spring into engagement with the other post.

2. A push-button switch, having in combination, a casing, an annular flange at the flaring end of the bell-like casing, a spacing ring continuing the annular flange, a pair of perforations provided with annular prongs on the end of the flange, and a pair of ears

integral with the spacing ring and provided with perforations having prongs, a strip of insulating material having perforations in its ends at which the prongs of the annular flange and the prongs of the ears may be received when the ears are turned over, a pair of binding posts carried by the insulating strip, a contact spring attached to one binding post, and a push button for

forcing the contact spring into engagement 10 with the other binding post.

In testimony whereof, I sign this specification in the presence of two witnesses.

WILLIAM W. BARRY, JR.
